ABSTRACT OF THE DISCLOSURE

Benzoyl ureas of the formula

and salts thereof with physiologically acceptable acids, useful as psychopharmacological agents, wherein R₁ is one or more of hydrogen, halogen, alkyl having 1 to 6 carbon atoms, alkenyl having 3 to 6 carbon atoms, cycloalkyl of 3 to 7 carbon atoms, cycloalkenyl of 4 to 7 carbon atoms, aralkyl having 1 to 4 alkylene carbon atoms, phenyl, hydroxy, acyloxy, alkoxy having 1 to 6 carbon atoms, alkenyloxy having 3 to 6 carbon atoms, aralkoxy having 1 to 4 alkylene carbon atoms, aryloxy, trifluoro, or nitro, in any position, or represents two vicinal substituents which are members of a condensed 5- to 7-membered carbocyclic ring; R₂ is hydrogen, halogen, alkyl having 1 to 4 carbon atoms, or alkoxy having 1 to 4 carbon atoms; and A is alkylene having 2 to 6 carbon atoms.

The present invention relates to benzoyl ureas and to a process for their manufacture.

It is known that acyl ureas (ureides) have sedative or anti-convulsive activities [cf. for example G. Ehrhard and H. Ruschig, "Arzneimittel," pages 287 and 485, Weinheim/Bergstrasse, W. Germany (1968), German Pat. No. 225,710; F. A. Gibbs, G. M. Everett, R. K. Richard, "Diseases Nerv. System 10, 47 (1949)].

This invention provides novel benzoyl ureas of the formula I

as well as the salts thereof with physiologically acceptable acids, in which R₁ stands for hydrogen, halogen, alkyl of 1 to 6 carbon atoms, alkenyl of 3 to 6 carbon atoms, cycloalkyl of 3 to 7 carbon atoms, cycloalkenyl of 4 to 7 carbon atoms, aralkyl of 1 to 4 alkylene carbon atoms, phenyl, hydroxy, acyloxy, alkyloxy of 1 to 6 carbon atoms, alkenyloxy of 3 to 6 carbon atoms, aralkoxy of 1 to 4 alkylene carbon atoms, aryloxy, trifluoromethyl or nitro, R₁ being one or more substituents in any position and two vicinal substituents optionally being also members of a condensed 5- to 7-membered carbocyclic ring, R₂ stands for hydrogen, halogen; alkyl of 1 to 4 carbon atoms or alkoxy of 1 to 4 carbon atoms, and A stands for alkylene of 2 to 6 carbon atoms.

The benzoyl ureas of the formula I and the cited salts thereof have valuable pharmacological properties and may be used as psycho-pharmacological agents, which especially have a muscle relaxing effect.

Among the compounds of the formula I, those compounds are preferred in which R₁ stands for hydrogen, fluorine, chlorine, bromine, alkyl of 1 to 4 carbon atoms,

2

cycloalkyl of 5 or 6 carbon atoms, benzyl, phenylethyl, phenyl, alkyloxy of 1 to 4 carbon atoms, phenylalkoxy of 1 or 2 alkylene carbon atoms, phenoxy, methoxy-phenoxy, trifluoromethyl, methylene-dioxy, ethylene-dioxy or butylene-1,4, and R₂ stands for hydrogen, fluorine, chlorine, bromine, methyl, ethyl, methoxy or ethoxy.

In addition to the substances cited in the Examples, there are especially mentioned:

- N-(4-cyclohexyl-benzoyl)-N'-(3-(4-m-tolyl-piperazin-1-yl)-propyl]-urea,
 N-(4-cyclopentyl-benzoyl)-N'-(3-(4-m-tolyl-piperazin-1-yl)-propyl]-urea,
 N-(4-n-hexyl-benzoyl)-N'-(3-(4-m-tolyl-piperazin-1-yl)-propyl]-urea,
 N-(4-benzyl-benzoyl)-N'-(3-(4-m-tolyl-piperazin-1-yl)-propyl]-urea,
 N-(4-phenylethyl-benzoyl)-N'-(3-(4-m-tolyl-piperazin-1-yl)-propyl]-urea,
 N-(2-phenyl-benzoyl)-N'-(3-(4-m-tolyl-piperazin-1-yl)-propyl]-urea,
 N-(3-butoxy-benzoyl)-N'-(3-(4-m-tolyl-piperazin-1-yl)-propyl]-urea,
 N-(4-benzyloxy-benzoyl)-N'-(3-(4-m-tolyl-piperazin-1-yl)-propyl]-urea,
 N-(2-phenoxy-benzoyl)-N'-(3-(4-m-tolyl-piperazin-1-yl)-propyl]-urea,
 N-(4-p-methoxy-phenoxy-benzoyl)-N'-(3-(4-m-tolyl-piperazin-1-yl)-propyl]-urea,
 N-(4-methoxy-benzoyl)-N'-(6-(4-m-tolyl-piperazin-1-yl)-hexyl]-urea,
 N-(3,4-dimethoxy-benzoyl)-N'-(3-(4-m-ethyl-phenyl-piperazin-1-yl)-propyl]-urea,
 N-(2,5-dimethyl-benzoyl)-N'-(3-(4-p-ethoxyphenyl-piperazin-1-yl)-propyl]-urea,
 N-(3,4,5-triethoxy-benzoyl)-N'-(3-(4-m-tolyl-piperazin-1-yl)-propyl]-urea,
 N-(1-naphthoyl)-N'-(3-(4-m-tolyl-piperazin-1-yl)-propyl]-urea,
 N-(5,6,7,8-tetrahydro-1-naphthoyl)-N'-(3-(4-m-tolyl-piperazin-1-yl)-propyl]-urea.

This invention also provides a process for the manufacture of benzoyl ureas of the formula I, wherein

- (a) an R₁-substituted benzoyl-isocyanate, benzoyl-carbamic acid ester, benzoyl-carbamic acid halide, benzoyl-thiobacamic acid ester, benzoyl-urea, benzoyl-semicarbazide or benzoyl-semicarbazone, is reacted with an amine of the formula II

in which A and R₂ are defined as above, or with a salt thereof, or a benzamide of the formula III

is reacted with an isocyanate, carbamic acid ester, thiobacamic acid ester, carbamic acid halide or urea, all substituted by the group

or

- (b) a correspondingly substituted benzoyl-isourea ether, benzoyl-isourea ester, benzoyl-isothiourea ether, ben-

- zoyl-parabanic acid or benzoyl-haloformic acid amidine, is hydrolyzed, or
- (c) a correspondingly substituted benzoyl-thiourea, thio-benzoyl-urea or thio-benzoyl-thiourea, all corresponding to the substituent R_1 , is treated with a reagent able to replace the sulfur atom by an oxygen atom, or
- (d) water is added on a correspondingly substituted benzoyl-carbodiimide, or
- (e) a R^1 -substituted benzoic acid or a halide, ester or anhydride thereof is reacted with a urea substituted by the group

- or a salt thereof, or
- (f) a compound of the formula IV

preferably in the form of a reactive ester, is reacted with a piperazine of the formula V

or

- (g) a compound of the formula VI

in which B stands for the radical

preferably in the form of a reactive ester, is reacted with an amine of the formula

or a compound of the formula VI, in which B stands for the radical

preferably in the form of its reactive ester, is reacted with an amine of the formula

The compound obtained according to the reactions (a) to (g) is optionally converted with a physiologically acceptable acid into the corresponding salt.

The benzoyl radical of the formula

may be varied within wide limits by substitution without substantially affecting the pharmacological activity of the products. The Examples hereinafter indicated refer to this fact; the process of the invention is, however, not limited to the use of the acyl radicals indicated therein; substances containing the indicated acyl radicals as well as other acyl radicals may be prepared according to the process and used as psychopharmacological agents.

The phenyl radical

may also carry a variety of substituents. As substituted phenyl radicals, there may be mentioned ortho-, meta- and para-tolyl, ortho-, meta- and para-methoxy-phenyl, 2-chloro-4-methyl-phenyl and other radicals. The m-tolyl radical is preferred.

The alkylene radical A having 2 to 6 carbon atoms may especially be an ethylene, 1,2-propylene, 1,3- or 2,4-butylene, tetra- or penta-methylene, preferably a trimethylene radical.

The preferred method (a) for the manufacture of the compounds of the invention from benzoyl isocyanate and an amine of the formula II may be carried out without using a solvent; it is, however, advantageous to use an inert solvent, such as ether, methylene chloride, dichloro-ethane, benzene, chlorobenzene, nitrobenzene, toluene or dimethylformamide. The reaction temperature may generally be between room temperature and the boiling temperature of the solvent used. For example, the reaction may be started at about 20° C. by adding a solution of the amine in toluene dropwise to a solution of benzoyl isocyanate in toluene, whereupon an increase in temperature is generally observed. The reaction temperature is advantageously between 30° and 100° C.; lower and higher temperature only influence the reaction rate.

The benzoyl-isocyanates to be used as starting material may be prepared in known manner, for example by reacting corresponding benzoyl-halides with metal salts of cyanic acid or from the corresponding acid amides.

According to method (a), the chlorides are preferably used as benzoyl-carbamic acid halides.

Moreover, according to method (a), a benzoyl-carbamic acid ester, benzoyl-thiocarbamic acid ester, benzoyl-urea, benzoyl-semicarbazide or benzoyl-semicarbazone is reacted with an amine of the formula II. Alternatively, the functional groups in the reaction components may also be exchanged so that an aromatic carboxylic acid amide of the formula III is reacted with an aryl-piperazino-alkyl-isocyanate, aryl-piperazino-alkyl-carbamic acid ester, aryl-piperazino-alkyl-thiolcarbamic acid ester, aryl-piperazino-alkyl-carbamic acid halide or aryl-piperazino-alkyl-urea. The reaction generally requires elevated temperatures, preferably between 80° and 180° C.

Benzoyl-carbamic acid esters and benzoyl-ureas to be used as starting material according to method (a) may be obtained from benzoyl-isocyanates and alcohols or amines or by acylation of urethanes and ureas, for example by a reaction with the corresponding carboxylic acid chlorides.

The benzoyl-carbamic acid esters or benzoyl-thiolcarbamic acid esters may contain, in the alcohol component, an alkyl radical or an aryl radical or even a heterocyclic radical. Since this radical is split off during the reaction, its chemical constitution has no influence on the nature of the end product and can therefore be varied within wide limits. The same applies to the carbamic acid esters substituted by the group

or the corresponding thiolcarbamic acid esters.

The benzoyl-ureas to be used as starting material for method (a) may be unsubstituted or mono- or disubstituted at the side of the urea molecule which is opposite to the benzoyl group. Since these substituents are split off in the reaction with amines, they may be varied within wide limits. In addition to benzoyl-ureas containing alkyl, aryl, acyl or heterocyclic groups, bis-acyl-ureas which may carry a further substituent at one of the nitrogen atoms, for example methyl, may also be used. For example, such

bis-acyl-ureas or N-benzoyl-N'-benzoyl-ureas may be treated with amines of the formula

by heating them to elevated temperatures, especially above 100° C.

It is furthermore possible to start from ureas of the formula

or from ureas which carry one or two substituents at the free nitrogen atom, and to react them with amides of the formula

As such starting materials, there are mentioned, for example:

N-[3-(4-m-tolyl-piperazin-1-yl)-propyl]-urea,
 N-[4-(4-m-tolylpiperazin-1-yl)-butyl]-urea,
 N-[5-(4-m-tolylpiperazin-1-yl)-pentyl]-urea,
 N-[3-(4-m-tolylpiperazin-1-yl)-butyl]-urea,
 N-[2-methyl-3-(4-m-tolylpiperazin-1-yl)-propyl]-urea,
 N-[4-(4-m-tolylpiperazin-1-yl)-butyl-(2)]-urea,
 N-[3-(4-p-fluorophenylpiperazin-1-yl)-propyl]-urea,
 N-[3-(4-m-chlorophenylpiperazin-1-yl)-propyl]-urea,
 N-[3-(4-phenylpiperazin-1-yl)-propyl]-urea,
 N-[3-(4-p-methoxyphenyl-piperazin-1-yl)-propyl]-urea,
 N-[3-(4-m-ethylphenyl-piperazin-1-yl)-propyl]-urea,

the corresponding N'-acetyl-, N'-nitro-, N'-aryl-piperazino-alkyl-, N',N'-diphenyl- (the two phenyl radicals may also be substituted or linked to each other directly or via a bridge member, such as $-\text{CH}_2-$, $-\text{NH}-$, $-\text{O}-$ or $-\text{S}-$), N'-methyl-N'-phenyl- and N',N'-dicyclohexyl-ureas.

According to method (b), the hydrolysis of the cited starting substances is advantageously carried out in an alkaline medium. The cited isourea ethers and isourea esters may also be hydrolyzed in an acid medium.

According to method (c), the replacement of the sulfur atom by the oxygen atom in the cited starting substances is performed, for example, with the aid of heavy metal oxides, such as lead oxide or mercury oxide, or heavy metal salts, such as lead nitrate, or by means of oxidizing agents such as hydrogen peroxide, sodium peroxide, or nitrous acid.

The benzoyl-carbodiimides to be used according to method (d) may be obtained as intermediate products in the desulfurization of benzoyl-thioureas according to method (c). They may also be prepared by reacting benzoyl-thioureas with acylating agents such as phosgene, or with phosphorus pentachloride. By an addition reaction with water they are converted into acylureas.

Method (e) is carried out in the presence or absence of basic condensation agents, such as tertiary organic bases, alkali metal or alkaline earth metal carbonates, hydroxides, hydrides, amides or the metals themselves, advantageously in inert solvents. As acid anhydrides which react in a manner similar to that of acid chlorides, mixed anhydrides may also be used. The reaction of the acid anhydrides may also be promoted by means of acid catalysts, such as sulfuric acid, perchloric acid, aluminum chloride or ion(III) chloride, instead of the basic condensation agents.

In method (e), esters of low molecular weight alcohols, of benzyl alcohols or of phenols are especially used as carboxylic acid esters. The reaction of these starting materials with the substituted ureas may advantageously be performed with the aid of alkali metals, alkali metal hydrides or amides in inert solvents, such as benzene,

toluene, dioxane, glycol ether, dimethyl-formamide, and sometimes also in liquid ammonia.

According to method (f), there may be used as reactive esters, for example, esters of hydrohalic acids, especially of hydriodic, hydrobromic and hydrochloric acids, and esters of sulfuric acid or of sulfonic acids, for example benzene- or toluene-sulfonic acid.

The reactive esters to be used according to method (g) are the same as mentioned for the afore-mentioned method (f).

The benzoyl-ureas of the invention may be employed in the form of the free bases and of the salts of physiologically acceptable acids. Suitable acids for salt formation are, for example, hydrochloric acid, hydrobromic acid and hydriodic acid, phosphoric acid, sulfuric acid, amidosulfonic acid, methyl-sulfuric acid, nitric acid, formic acid, acetic acid, propionic acid, succinic acid, tartaric acid, lactic acid, malonic acid, fumaric acid, citric acid, malic acid, mucic acid, benzoic acid, salicylic acid, aceturic acid, embonic acid, naphthalene-1,5-disulfonic acid, ascorbic acid, hydroxy-ethanesulfonic acid, benzene-sulfonic acid, or also synthetic resins containing acid groups.

The benzoyl-ureas of the invention have valuable pharmacodynamic properties. Especially on various kinds of animals they produce effects which mark them as psychopharmacological agents having a tranquilizing activity.

For example, N-(4-methoxybenzoyl) - N'-[3-(4-m-tolylpiperazin-1-yl)-propyl]-urea hydrochloride or N-(5-chloro-2-methoxybenzoyl)-N'-[3-(4-m-tolylpiperazin-1-yl)-propyl]-urea dihydrochloride shows a muscle-relaxing effect which is several times stronger than that of meprobamate. The period of action is also substantially longer than that of the known compound.

Moreover, in a test on animals, the benzoyl-ureas of the invention exhibit a protection effect against lethal nicotine dosages and prolong an anaesthesia initiated by barbiturates or alcohol. In the pentetrazol test, the novel benzoyl-ureas bring about intensification of a spasm similar to the accumulative effect of the psychopharmacological agents of the amitriptyline type.

Within the group of the benzoyl-ureas of the invention, there are distinct differences in the activity of individual substances in the somnolence test. In contrast to other compounds of the invention, N-(5-chloro-2-methoxy-benzoyl)-N'-[3-(4-m-tolylpiperazin-1-yl)-propyl]-urea dihydrochloride causes practically no somnolence in a test on animals. Thus, it is possible to select from the group of benzoyl-ureas those compounds which meet various requirements according to each individual case.

The toxicity of the acyl-ureas of the invention is very low. For example, the lethal dose LD₅₀ of the two above-mentioned hydrochlorides, administered to mice per os, i.e. the dose that kills 50 percent of the test animals, is about twice as high as that of meprobamate.

For the treatment of psychic diseases, the novel benzoyl-ureas may be administered parenterally, preferably orally, for example in the form of tablets or dragees. For the manufacture of the compositions, the usual carriers and adjuvants, such as lactose, starch, tragacanth, magnesium stearate, are used.

The following Examples serve to illustrate the invention.

EXAMPLES

1. A solution of 105 g. of 3-(4-m-tolylpiperazin-1-yl)-propylamine in 200 ml. of toluene was added dropwise, while stirring, to a solution of 79.6 g. of 4-methoxybenzoyl-isocyanate in 400 ml. of toluene, while the internal temperature rose above 50° C. Stirring was then continued for about 3 hours. The reaction solution was evaporated and the residue was converted into the hydrochloride by means of methanolic hydrochloric acid. 160 g. of N-(4-methoxybenzoyl)-N'-[3-(4-m-tolyl-

- piperazin-1-yl) propyl]-urea hydrochloride were obtained, melting point 218-220° C. In an analogous manner there were obtained:
2. N-benzoyl-N'-[3-(4-m-tolylpiperazin-1-yl)-propyl]-urea dihydrochloride, m.p. 215-217° C.; the monohydrochloride melted at 235-236° C.
  3. N-(2-methoxy-benzoyl)-N'-[3-(4-m-tolylpiperazin-1-yl)-propyl]-urea dihydrochloride, m.p. 182-184° C.
  4. N-(3-methoxy-benzoyl)-N'-[3-(4-m-tolylpiperazin-1-yl)-propyl]-urea dihydrochloride, m.p. 212-214° C.
  5. N-(5-chloro-2-methoxy-benzoyl)-N'-[3-(4-m-tolylpiperazin-1-yl)-propyl]-urea dihydrochloride, m.p. 189-190° C.
  6. N-(3,4,5-trimethoxy-benzoyl)-N'-[3-(4-m-tolylpiperazin-1-yl)-propyl]-urea dihydrochloride, m.p. 202-204° C.
  7. N-benzoyl-N'-[3-(4-o-tolylpiperazin-1-yl)-propyl]-urea dihydrochloride, m.p. 195-196° C.
  8. N-benzoyl-N'-[3-(4-p-tolylpiperazin-1-yl)-propyl]-urea dihydrochloride, m.p. 208-210° C.
  9. N-benzoyl-N'-[4-(4-m-tolylpiperazin-1-yl)-butyl]-urea dihydrochloride, m.p. 210° C.
  10. N-(4-chlorobenzoyl)-N'-[3-(4-m-tolylpiperazin-1-yl)-propyl]-urea dihydrochloride, m.p. 219-221° C.
  11. N-(2-methyl-benzoyl)-N'-[3-(4-m-tolylpiperazin-1-yl)-propyl]-urea dihydrochloride, m.p. 220-222° C.
  12. N-(4-methyl-benzoyl)-N'-[3-(4-m-tolylpiperazin-1-yl)-propyl]-urea dihydrochloride, m.p. 220-221° C.
  13. N-(3-methyl-benzoyl)-N'-[3-(4-m-tolylpiperazin-1-yl)-propyl]-urea dihydrochloride, m.p. 212-214° C.
  14. N-(3,4-methylene-dioxybenzoyl)-N'-[3-(4-m-tolylpiperazin-1-yl)-propyl]-urea dihydrochloride, m.p. 240-242° C.
  15. N-(2-methoxy-5-methyl-benzoyl)-N'-[3-(4-m-tolylpiperazin-1-yl)-propyl]-urea dihydrochloride, m.p. 186-188° C.
  16. N-(2,5-dimethyl-benzoyl)-N'-[3-(4-m-tolylpiperazin-1-yl)-propyl]-urea, m.p. 167-168° C.
  17. N-(3,4-dimethoxy-benzoyl)-N'-[3-(4-m-tolylpiperazin-1-yl)-propyl]-urea dihydrochloride, m.p. 160° C.
  18. N-benzoyl-N'-[2-(4-m-tolylpiperazin-1-yl)-ethyl]-urea dihydrochloride, m.p. 232-234° C.
  19. N-benzoyl-N'-[3-(4-o-chloro-p-tolylpiperazin-1-yl)-propyl]-urea hydrochloride, m.p. 237-239° C.
  20. N-(3,5-dimethoxy-benzoyl)-N'-[3-(4-m-tolylpiperazin-1-yl)-propyl]-urea dihydrochloride, m.p. 195-196° C.
  21. N-(3-trifluoromethyl-benzoyl)-N'-[3-(4-m-tolylpiperazin-1-yl)-propyl]-urea dihydrochloride, m.p. 217-219° C.
  22. N-benzoyl-N'-[3-(4-m-tolylpiperazin-1-yl)-butyl]-urea dihydrochloride, m.p. 213-233° C.
  23. N-(3-fluorobenzoyl)-N'-[3-(4-m-tolylpiperazin-1-yl)-propyl]-urea dihydrochloride, m.p. 217-218° C.
  24. N-benzoyl-N'-[2-methyl-3-(4-m-tolylpiperazin-1-yl)-propyl]-urea hydrochloride, m.p. 245-247° C.
  25. N-(2,6-dimethoxy-benzoyl)-N'-[3-(4-m-tolylpiperazin-1-yl)-propyl]-urea dihydrochloride, m.p. 184° C.
  26. N-benzoyl-N'-[3-(4-m-methoxyphenylpiperazin-1-yl)-propyl]-urea dihydrochloride, m.p. 205-208° C.
  27. N-(2-ethoxy-benzoyl)-N'-[3-(4-m-tolylpiperazin-1-yl)-propyl]-urea dihydrochloride, m.p. 193-195° C.
  28. N-benzoyl-N'-[3-(4-p-methoxyphenylpiperazin-1-yl)-propyl]-urea dihydrochloride, m.p. 218-219° C.
  29. N-benzoyl-N'-[3-(4-m-chlorophenylpiperazin-1-yl)-propyl]-urea hydrochloride, m.p. 207-209° C.
  30. N-benzoyl-N'-[3-(4-o-methoxyphenylpiperazin-1-yl)-propyl]-urea dihydrochloride, m.p. 216-218° C.
  31. N-(4-fluorobenzoyl)-N'-[3-(4-m-tolylpiperazin-1-yl)-propyl]-urea hydrochloride, m.p. 244-245° C.
  32. N-(4-tert-butylbenzoyl)-N'-[3-(4-m-tolylpiperazin-1-yl)-propyl]-urea dihydrochloride, m.p. 218-220° C.
  33. N-(4-cyclohexyl-benzoyl)-N'-[3-(4-m-tolylpiperazin-1-yl)-propyl]-urea from 4-cyclohexylbenzoyl-is-

- cyanate and 3-(4-m-tolylpiperazin-1-yl)propyl-amine.
34. N-(4-cyclopentyl-benzoyl)-N'-[3-(4-m-tolylpiperazin-1-yl)-propyl]-urea from 4-cyclopentyl-benzoyl-isocyanate and 3-(4-m-tolylpiperazin-1-yl)-propyl-amine.
  35. N-(4-n-hexyl-benzoyl)-N'-[3-(4-m-tolylpiperazin-1-yl)-propyl]-urea from 4-n-hexylbenzoyl-isocyanate and 3-(4-m-tolylpiperazin-1-yl)-propyl-amine.
  36. N-(4-benzyl-benzoyl)-N'-[3-(4-m-tolylpiperazin-1-yl)-propyl]-urea from 4-benzylbenzoyl-isocyanate and 3-(4-m-tolylpiperazin-1-yl)-propyl-amine.
  37. N-(4-phenethyl-benzoyl)-N'-[3-(4-m-tolylpiperazin-1-yl)-propyl]-urea from 4-phenethylbenzoyl-isocyanate and 3-(4-m-tolylpiperazin-1-yl)-propyl-amine.
  38. N-(2-phenylbenzoyl)-N'-[3-(4-m-tolylpiperazin-1-yl)-propyl]-urea from 2-phenylbenzoyl-isocyanate and 3-(4-m-tolylpiperazin-1-yl)-propyl-amine.
  39. N-(3-butoxybenzoyl)-N'-[3-(4-m-tolylpiperazin-1-yl)-propyl]-urea from 3-butoxybenzoyl-isocyanate and 3-(4-m-tolylpiperazin-1-yl)-propyl-amine.
  40. N-(4-benzoyloxy-benzoyl)-N'-[3-(4-m-tolylpiperazin-1-yl)-propyl]-urea from 4-benzoyloxybenzoyl-isocyanate and 3-(4-m-tolylpiperazin-1-yl)-propyl-amine.
  41. N-(2-phenoxybenzoyl)-N'-[3-(4-m-tolylpiperazin-1-yl)-propyl]-urea from 2-phenoxybenzoyl-isocyanate and 3-(4-m-tolylpiperazin-1-yl)-propyl-amine.
  42. N-(4-p-methoxyphenoxy-benzoyl)-N'-[3-(4-m-tolylpiperazin-1-yl)-propyl]-urea from 4-p-methoxyphenoxybenzoyl-isocyanate and 3-(4-m-tolylpiperazin-1-yl)-propyl-amine.
  43. N-(4-methoxybenzoyl)-N'-[6-(4-m-tolylpiperazin-1-yl)-hexyl]-urea from 4-methoxybenzoyl-isocyanate and 6-(4-m-tolylpiperazin-1-yl)-hexyl-amine.
  44. N-(3,4-methylenedioxy-benzoyl)-N'-[3-(4-phenylpiperazin-1-yl)-propyl]-urea from 3,4-methylenedioxybenzoyl-isocyanate and 3-(4-phenylpiperazin-1-yl)-propyl-amine.
  45. N-(3-methoxybenzoyl)-N'-[3-(4-m-tolylpiperazin-1-yl)-propyl]-urea from 3-methoxybenzoyl-isocyanate and 3-(4-m-bromo-phenylpiperazin-1-yl)-propyl-amine.
  46. N-(3,4-dimethoxybenzoyl)-N'-[3-(4-m-ethylphenylpiperazin-1-yl)-propyl]-urea from 3,4-dimethoxybenzoyl-isocyanate and 3-(4-m-ethylphenylpiperazin-1-yl)-propyl-amine.
  47. N-(2,5-dimethylbenzoyl)-N'-[3-(4-p-ethoxyphenylpiperazin-1-yl)-propyl]-urea from 2,5-dimethylbenzoyl-isocyanate and 3-(4-p-ethoxyphenylpiperazin-1-yl)-propyl-amine.
  48. N-(3,4,5-triethoxybenzoyl)-N'-[3-(4-m-tolylpiperazin-1-yl)-propyl]-urea from 3,4,5-triethoxybenzoyl-isocyanate and 3-(4-m-tolylpiperazin-1-yl)-propyl-amine.
  49. N-(1-naphthoyl)-N'-[3-(4-m-tolylpiperazin-1-yl)-propyl]-urea from 1-naphthoylisocyanate and 3-(4-m-tolylpiperazin-1-yl)-propyl-amine.
  50. N-(5,6,7,8-tetrahydro-1-naphthoyl)-N'-[3-(4-m-tolylpiperazin-1-yl)-propyl]-urea from 5,6,7,8-tetrahydro-1-naphthoylisocyanate and 3-(4-m-tolylpiperazin-1-yl)-propyl-amine.
  51. A mixture of 2.2 g. of 3-(4-m-tolylpiperazin-1-yl)-propyl-isocyanate, boiling point: 165-168° C. under a pressure of 0.3 mm. mercury, and 1.58 g. of 5-chloro-2-methoxy-benzamide was heated for some hours at 130-140° C. The reaction product was purified by fractionated elution from a silica gel column by means of a mixture of chloroform and methanol and converted into the dihydrochloride. 1.4 g. of N-(5-chloro-2-methoxy-benzoyl)-N'-[3-(4-m-tolylpiperazin-1-yl)-propyl]-urea dihydrochloride were obtained, which melted, after recrystallization from methanol at 189-190° C.
  - 51(a). 2.2 g. of 3-(4-m-tolylpiperazin-1-yl)-propyl-isocyanate and 1.58 g. of 5-chloro-2-methoxy-benzamide were heated at the boil for 6 hours in 50 ml. of benzene. After separation of benzene by distillation, the residue was heated for another 6 hours at 130-140° C. After having been cooled, the reaction product was taken up

in 100 ml. of methanol, the solution was acidified with alcoholic hydrogen chloride and ether was added. 2.8 g. of N-(5-chloro-2-methoxy-benzoyl)-N'-[3-(4-m-tolylpiperazin-1-yl)propyl]-urea dihydrochloride were obtained, m.p. 185-190° C. By recrystallization from aqueous methanol, the monohydrochloride was obtained, m.p. 189-191° C.

52. 6.05 g. of benzamide and 2.4 g. of a 50% suspension of sodium hydride in oil were heated for some hours at 80–90° C. in 100 ml. of xylene. The reaction mixture was combined, while stirring, at 60° C. with 17.7 g. of N-[3-(4-m-tolylpiperazin-1-yl)-propyl]-carbamic acid phenyl ester (m.p. of the hydrochloride: 159–161° C.) in 60 ml. of xylene. Heating was continued for 15 minutes at 80° C., the reaction mixture was allowed to cool, 250 ml. of methylene chloride were added and the solution was washed with water. The organic solution was dried with potassium carbonate and evaporated. 18 g. of N-benzoyl-N'-[3-(4-m-tolylpiperazin-1-yl)-propyl]-urea were obtained, which was recrystallized from methanol, m.p. 142–144° C.

53. The base prepared from 1.73 g. of N-benzoyl-N'-(3-(4-m-tolylpiperazin-1-yl)-propyl)-thiourea hydrochloride, m.p. 207-209° C., by means of aqueous sodium carbonate solution was heated, while vigorously stirring, for 1 hour at 65-70° C., with 1.2 g. of yellow mercury oxide in 50 ml. of ethanol. The reaction mixture was filtered by means of charcoal and the filtrate was neutralized with methanolic hydrochloric acid. 1.2 g. of N-benzoyl-N'-(3-(4-m-tolylpiperazin-1-yl)-propyl)-urea dihydrochloride were obtained, which was recrystallized from methanol, m.p. 215-217° C.

54. 1.1 g. of 5-chloro-2-methoxy-benzoyl chloride were introduced slowly while stirring at 5-10° C. into a solution of 1.38 g. of N-[3-(4-m-tolylpiperazin-1-yl)-propyl]-urea, m.p. 138-139° C., in 50 ml. of pyridine. The mixture was heated for 2 hours on a steam bath and the pyridine was separated by distillation. The residue was taken up in methylene chloride, the solution was washed with an aqueous sodium carbonate solution and water, dried with sodium sulfate and evaporated. The product was subjected to a fractionated elution through a silica gel column. 0.7 g. of N-(5-chloro-2-methoxy-benzoyl)-N'-[3-(4-m-tolylpiperazin-1-yl)-propyl]-urea was obtained, the dihydrochloride thereof had a melting point of 189-190° C. after recrystallization from methanol.

55. 1.64 g. of benzoyl-urea and 2.33 g. of 3-(4-m-tolyl-piperazin-1-yl)-propyl-amine were heated at the boil in 50 ml. of xylene for 10 hours. After cooling, the reaction product was suction-filtered and recrystallized from methanol. 2.5 g. of N-benzoyl-N'-[3-(4-m-tolylpiperazin-1-yl)-propyl]-urea were obtained, m.p. 142-144° C.

56. 5.1 g. of 4-benzoyl-1-phenyl-semicarbazide (m.p. 212–214° C. prepared by reacting benzoyl-isocyanate with phenyl-hydrazine) and 5 g. of 3-(4-m-tolylpiperazin-1-yl)-propylamine were heated at the boil for 10 hours in 100 ml. of xylene. After cooling, the product was suction-filtered and recrystallized from methanol. 3.5 g. of N-benzoyl-N'-[3-(4-m-tolylpiperazin-1-yl)propyl]-urea were obtained, m.p. 142–144° C.

57. 10 g. of N-benzoyl-carbamic acid ethyl ester and 11.7 g. of 3-(4-m-tolylpiperazin-1-yl)-propylamine were heated at 80° C. for 5 hours in 100 ml. of xylene in the presence of 0.5 g. of sodium methylate. The product obtained after distillation of the solvent was recrystallized from methanol. 5 g. of N-benzoyl-N'-(3-(4-m-tolylpiperazin-1-yl)propyl)-urea were obtained, m.p. 142-144° C.

58. 14.4 g. of 5-chloro-2-methoxy-benzamide and 2.5 g. of sodium hydride were heated at the boil for 2 hours in 100 ml. of benzene. After cooling, 100 ml. of dimethylformamide were added. A solution of 33 g. of N-[3-(4-m-tolylpiperazin-1-yl)-propyl]-carbamic acid phenyl ester in 50 ml. of benzene was added at about 40° C.

to this mixture, and stirring was continued for 2 hours at 45° C. The reaction solution was evaporated and the residue was recrystallized from methanol. 20 g. of N-(5-chloro - 2-methoxy-benzoyl)-N'-[3-(4-m-tolylpiperazin-1-yl)-propyl]-urea were obtained, m.p. 118-120° C.

When dimethylformamide or dioxan was used as a solvent instead of benzene, the same product was obtained.

10 59. 3 g. of 1-benzoyl-1-[3-4-m-tolylpiperazin-1-yl]-propyl-parabanic acid (m.p. 136-140° C., prepared by benzoylation of 1-[3-(4-m-tolylpiperazin-1-yl)propyl]-parabanic acid, the hydrochloride thereof melted at 245-250° C. with decomposition) were heated for 30 minutes in 50 ml. of boiling 1N sodium hydroxide solution. After cooling, the reaction product was suction-filtered and recrystallized from methanol. 1 g. of N-benzoyl-N'-[3 - (4-m-tolylpiperazin-1-yl)-propyl]-urea was obtained, m.p. 142-144° C.

60. 10 ml. of thionyl chloride were added at about 10° C. to 4.4 g. of N-benzoyl-N'-(3-hydroxy-propyl)-urea, m.p. 120-122° C., in 20 ml. of chloroform. The temperature was gradually raised to 30° C., stirring was continued for some time and the solution was evaporated under reduced pressure. The residue was taken up in 50 ml. of ethanol and, after addition of 16 g. of N-m-tolylpiperazine, the mixture was heated at the boiling point for about 15 hours. The reaction product was purified by fractionated elution from a silica gel column by means of a mixture of chloroform and methanol. 0.9 g. of N-benzoyl-N'-(3-(4-m-tolylpiper-)

methanol. 0.9 g. of N-benzoyl-N'-(3-(4-m-tolyl)piperazin-1-yl)-propyl-urea was obtained, m.p. 142-144° C. 61. 15 ml. of thionyl chloride were added at 5-10° C. to 3.5 g. of 1-benzoyl-3-(3-diethanol-aminopropyl)-urea hydrochloride, m.p. 112-115° C., in 20 ml. of chloroform. The temperature was slowly raised to 30° C. and the reaction mixture was evaporated under reduced pressure. The residue was taken up in 40 ml. of methanol and, after addition of 2.3 g. of m-toluidine, the solution was heated at the boiling point for 15 hours. The reaction mixture was then evaporated and the residue was treated with dilute sodium hydroxide solution and ether. The product obtained from the ether was purified by fractionated elution from a silica gel column by means of a mixture of methanol and carbon tetrachloride. 0.6 g. of N-benzoyl-N'-(3-(4-m-tolyl)piperazin-1-yl)-propyl-urea was obtained, m.p. 142-144° C.

What we claim is:

1. A benzoyl-urea of the formula

and salts thereof with physiologically acceptable acids, wherein R_1 is one to three substituents, in any position, selected from the group consisting of hydrogen, halogen, alkyl having 1 to 6 carbon atoms, alkenyl having 3 to 6 carbon atoms, cycloalkyl having 3 to 7 carbon atoms, cycloalkenyl having 4 to 7 carbon atoms, phenalkyl having 1 to 4 alkylene carbon atoms, phenyl, hydroxy, alkoxy having 1 to 6 carbon atoms, alkenoxy having 3 to 6 carbon atoms, phenalkoxy having 1 to 4 alkylene carbon atoms, phenoxy, methoxy-substituted phenoxy, trifluoromethyl, and nitro, or R_1 represents two vicinal substituents forming a condensed 6-membered carbocyclic or methylenedioxy ring with the phenyl group to which they are attached; R_2 is hydrogen, halogen, alkyl having 1 to 4 carbon atoms, or alkoxy having 1 to 4 carbon atoms, and A is alkylene having 2 to 6 carbon atoms.

2. N-(4-methoxy-benzyl)-N'-[3-(4-m-tolyl-piperazin-1-yl)-propyl]-urea hydrochloride.

11

3. N-(5 - chloro - 2 - methoxy-benzoyl)-N'-[3-(4-m-tolyl-piperazin-1-yl)-propyl]-urea monohydrochloride.

4. N-(5-chloro - 2 - methoxy-benzoyl-N'-[3-(4-m-tolyl-piperazin-1-yl)-propyl]-urea.

5. N-(3,4-methylene-dioxy-benzoyl) - N' - [3-(4-m-tolyl-piperazin-1-yl)-propyl]-urea dihydrochloride.

6. N-(2,5-dimethyl-benzoyl) - N' - [3-(4-m-tolyl-piperazin-1-yl)-propyl]-urea.

7. N-(1-naphthoyl) - N' - [3-(4-m-tolyl-piperazin-1-yl)-propyl]-urea.

8. N-(5,6,7,8-tetrahydro - 1 - naphthoyl)-N'-[3-(4-m-tolyl-piperazin-1-yl)-propyl]-urea.

12
